BELT ATTACHED FISH ROD HOLDER

Leon A. Polzin, P.O. Box 54, Cuero, Tex. 77954

Filed Dec. 19, 1974, Ser. No. 534,567

Term of patent 14 years

Int. Cl. D22—05

U.S. Cl. D22—14

FIG. 2

FIG. 3

FIG. 4

FIG. 5

FIG. 6

FIG. 1

FIG. 1 is a perspective view of a belt attached fish rod holder;

FIG. 2 is a top plan view of the belt attached fish rod holder of this invention;

FIG. 3 is a front elevational view of the belt attached fish rod holder;

FIG. 4 is a right side view of the belt attached fish rod holder of FIG. 3. The left side view is identical to the right side view;

FIG. 5 is a rear view of the fish rod holder; and

FIG. 6 is a bottom plan view of the belt attached fish rod holder.

I claim:

The ornamental design for a belt attached fish rod holder, as shown and described.
